UNITED STATES PATENT OFFICE.

FRANCIS JOSEPH MICHAEL MILES, OF CHICAGO, ILLINOIS, ASSIGNOR TO MELBA MANUFACTURING COMPANY, OF CHICAGO, ILLINOIS, A CORPORATION OF ILLINOIS.

DESIGN FOR A CONTAINER FOR TOILET POWDERS.

48,078.

Specification for Design.

Patented Nov. 2, 1915.

Application filed August 9, 1915. Serial No. 44,656. Term of patent 7 years.

To all whom it may concern:

Be it known that I, FRANCIS JOSEPH MICHAEL MILES, a citizen of the United States, residing at Chicago, in the county of Cook and State of Illinois, have invented a new, original, and ornamental Design for Containers for Toilet Powders, of which the following is a specification, reference being had to the accompanying drawing, forming a part thereof, in which—

Figure 1 is a perspective view of my design for containers for toilet powders, and Fig. 2 a section showing the rectangular base of the same.

I claim—

The ornamental design for a container for toilet powders as shown.

FRANCIS JOSEPH MICHAEL MILES.
